EARTH ANCHOR

David C. Hubbard, Centralia, Mo., assignor to
 A. B. Chance Company, Centralia, Mo., a corporation of Missouri

Application November 7, 1942, Serial No. 464,916

2 Claims. (Cl. 189—92)

The present invention relates to earth anchors, and is particularly concerned with that type of earth anchor adapted to be inserted in a bored hole by means of a guy rod and adapted to have its movable wings expanded into engagement with the undisturbed earth surrounding the bore.

One of the objects of the invention is the provision of an improved earth anchor adapted to utilize a minimum amount of metal and having the major portion of its structure made of non-metallic materials, such as hard wood, which are readily available in spite of the present scarcity of metal.

Another object of the invention is the provision of an improved earth anchor of the class described, which is provided with an improved form of expanding wings, which are adapted to be guided more certainly into the proper expanded position.

Another object of the invention is the provision of an improved anchor structure of the class described, in which the expanding wings are suitably pivoted together and centered on the guy rod in such manner that they cannot get out of proper alignment and so that they are adapted to be expanded equally toward both sides.

Another object of the invention is the provision of an improved expanding anchor of the class described provided with suitable means for spreading the thrust force on the anchor over a predetermined area for increasing the strength of the assembly and increasing the resistance toward movement of the expanded anchor.

Another object of the invention is the provision of an improved expanding anchor adapted to be constructed of wood, and which is adapted to be manufactured at a low cost, and which is sturdy, and capable of being used for a long period of time.

Another object of the invention is the provision of an improved expanding anchor adapted to be constructed of wood, which is adapted to utilize to the fullest extent the ultimate holding power of the soil in which it is to be used.

Another object of the invention is the provision of an expanding anchor adapted to be constructed of wood, which is so constructed as to permit the salvage of the guy rod by abandoning the anchor and screwing the guy rod out of the threaded member which is located below the anchor.

Other objects and advantages of the invention will be apparent from the following description and the accompanying drawing, in which simi-

lar characters of reference indicate similar parts throughout the separate views.

Fig. 1 is a side elevational view of an anchor embodying my invention in which the anchor wings are secured together at the top by a pair of bendable strips;

Fig. 2 is a side elevational view of the anchor of Fig. 1, taken from the right side of Fig. 1, also showing a feature which permits the salvage of the guy rod;

Fig. 3 is a view showing the preferred form of anchor in expanded position;

Fig. 4 is a top plan view of the anchor in the position of Fig. 2; and

Fig. 5 is a top plan view of the anchor in the position of Fig. 3.

Referring to the drawing, Figs. 1 to 5, 10 indicates an anchor assembly which preferably includes a guy rod 11, an expanding or wedging member 12, and a pair of anchor wings 13, 14. The guy rod 11 is preferably of the type having a suitable eye at its upper end for engagement with a cable, and having a lower threaded end portion 15 provided with a nut 16.

25 The nut preferably engages a metal pressure plate 17 for distributing the thrust caused by a pull on the guy rod over a larger area of the expanding member 12.

The expanding member 12 and wings 13, 14 are preferably made of hard wood, such as oak. The expanding member may comprise a substantially cylindrical wooden body, having a plane lower surface 18 for engagement with the thrust plate 17.

35 This expanding member is provided with a cylindrical through bore 19 for passing the guy rod 11. At its upper end its diametrically opposite sides are provided with beveled, sloping, camming surfaces 20, 21, which take the form 40 of plane surfaces, having a curved lower boundary, as shown in Fig. 1.

The anchor wings 13, 14 are preferably similar in shape and structure, but are oppositely located. Each of these wings may comprise a 45 flat wooden member having the plane upper and lower surfaces 22, 23.

The upper corner is preferably beveled off at 24, and the end corner may be beveled off at 25 (Fig. 5). At the lower inner side of each wing 50 13, 14 there is a beveled camming surface 26 or 27, and these beveled camming surfaces preferably have the same angle with respect to the major axis of each wing as the angularity of the camming surfaces 20, 21 on the wedge 12.

55 Thus these end portions 26, 27 preferably fit

against the camming surfaces 20, 21 when the anchor is not expanded as shown in Fig. 2.

The two wings each have a partially cylindrical groove 28 or 29, forming an oval bore slightly larger than the diameter of the guy rod, as shown in Fig. 5, so that there will be room for the guy rod, even when the wings pivot out to the position of Fig. 4.

The two wings are preferably secured together by a hinge means, which may consist of a pair of flexible straps of bendable material, preferably metal. These straps are indicated by the numerals 50 and 51. Each strap is of substantially U shape, and it is provided with apertures in its legs for receiving the wood screws 52, 53, 15 which secure the straps to the blades 13, 14.

The straps are preferably symmetrically located on the opposite sides of the guy rod 11, and banding may take place in the strap at any point in the top part or yoke 54 when the wings 20 are expanded as shown in Fig. 3.

Another feature of this anchor is that the nut 16 may be welded as at 55 to the pressure plate 17, and the pressure plate 17 may be secured by means of the screw bolts 56 and 57 to the bottom of the body 12. Thus, the nut cannot turn without turning the body when the guy rod 11 is rotated, and after the anchor has been expanded as shown in Fig. 3 the guy rod may be removed by rotating it in a counter-clockwise direction, while the nut, plate, and anchor are held in fixed position by the earth. This permits the salvage of the guy rod when the anchor is no longer to be used.

The operation of the earth anchor is as follows:

A bore is made in the earth, usually extending diagonally into the ground in the direction in which the guy rod is to extend. This bore is preferably only slightly larger than the external diameter of the contracted anchor assembly shown in Fig. 4.

The anchor is placed on the guy rod; and using the guy rod as a handle, the anchor assembly is moved to the bottom of the bore in the earth. A tamping member, which preferably engages both wings at once, and has a slot for the guy rod 11, is then used to tamp on the ends of the wings, forcing them downward.

The camming surfaces 26, 27 slidably engage the camming surfaces 20, 21 and cause the wings to expand, and the relatively sharp points 42 on the wings cause them to penetrate the earth as the wings expand.

In Fig. 3 the anchor is shown in fully expanded position; and it is found that by means of this specific structure the holding power of the anchor is increased approximately three hundred percent, over a similar expanded anchor the blades of which are not joined or hinged at the top.

The increased holding power of an anchor constructed according to the invention, over an unexpanded anchor of the same size but not adapted to engage the undisturbed earth, would be on the order of one thousand percent.

The value of the expanding blades in the anchor constructed according to the invention, lies in the fact that they penetrate into undisturbed earth, having a much higher retaining strength than the disturbed earth that is retamped into the hole.

One of the important features of the invention is that the blades shall be secured together at the top by some means for preventing spreading. 75

The slope of the blades then acts in a manner similar to a cone anchor in projecting the pulling force against solid earth and developing the full shear strength of the soil for the area of the expanded anchor.

With regard to the cylindrical shape of the body 12, it is found by test that satisfactory holding power is effected by using a square base, arranged with bevel 42 on the flat faces of the square and also with the bevel arranged diagonally across the opposite corners of a square base. This structure has the advantage of being more economical and of giving good holding power results.

Such an anchor, however, was not capable of utilizing the ultimate strength of the soil as the anchors of square shape reached their ultimate strength and were completely destroyed, whereas the anchors with the round base as shown herein attain the ultimate strength of the soil without serious damage to the anchor.

It will thus be observed that I have invented an improved form of earth anchor, most of the parts of which may be made out of wood, so that metal may be conserved and suitable anchors provided at a minimum cost.

The present anchors are sturdy and serviceable when made out of hard wood or wood which has a minimum tendency to rot, and they provide a firm anchorage for guy rods which will enable them to replace the metal anchors of the prior art.

While I have illustrated a preferred embodiment of my invention, many modifications may be made without departing from the spirit of the invention, and I do not wish to be limited to the precise details of construction set forth, but desire to avail myself of all changes within the scope of the appended claims.

Having thus described my invention, what I claim as new and desire to secure by Letters Patent of the United States, is:

1. In an earth anchor the combination of a substantially cylindrical body having an axially extending bore with a guy rod having a threaded lower end, extending through and projecting from said bore, said cylindrical member having a pair of diametrically oppositely disposed acutely beveled surfaces on its upper end and having means on its lower end for supporting and preventing rotation of a nut carried by the threaded end of said guy rod, a pair of expanding members comprising thick members, one disposed on each side of said guy rod and extending longitudinally of said guy rod, said expanding members being provided on their inner lower sides with acutely beveled surfaces substantially parallel to the beveled surfaces on said cylindrical member, thereby forming sharp edges at the outer lower portions of said expanding members, and said expanding members being formed at their upper edges with flat surfaces for engagement with a tamping bar, and a pair of bendable metal straps located on each side of said guy rod, said straps being secured to said expandable members with the expandable members in the folded position which is substantially parallel to said guy rod whereby an axial thrust applied to the expandable members at their upper ends causes the expandable members to be spread due to the camming action of the said beveled surfaces until the expandable members have their sharp edges driven into the adjacent earth in an anchor hole.
2. In an earth anchor the combination of a

substantially cylindrical body having an axially extending bore with a guy rod having a threaded lower end, extending through and projecting from said bore, said cylindrical member having a pair of diametrically oppositely disposed acutely beveled surfaces on its upper end and having means on its lower end for supporting and preventing rotation of a nut carried by the threaded end of said guy rod, a pair of expanding members comprising thick members, one disposed on each side of said guy rod and extending longitudinally of said guy rod, said expanding members being provided on their inner lower sides with acutely beveled surfaces substantially parallel to the beveled surfaces on said cylindrical member, thereby forming sharp edges at the outer lower portions of said expanding members, and said expanding

members being formed at their upper edges with flat surfaces for engagement with a tamping bar, and a pair of bendable metal straps, one located on each side of said guy rod, said straps being secured to said expandable members with the expandable members in the folded position which is substantially parallel to said guy rod, whereby an axial thrust applied to the expandable members at their upper ends causes the expandable members to be spread due to the camming action of the said beveled surfaces until the expandable members have their sharp edges driven into the adjacent earth in an anchor hole, said straps being of substantially U-shape and the downwardly extending legs of each strap engaging outside of said expanding members.

DAVID C. HUBBARD.
